N-SECONDARY-ALKYL-2-(3-HYDROXYPHENYL)-2-ETHYL-ALKYLAMINES

Walter Krohs, Bad Soden, Taunus, Leopold Ther and Gerhard Vogel, Frankfurt am Main, and Heinrich Ott, Eppstein, Taunus, Germany, assignors to Farbwerke Hoechst Aktiengesellschaft vormals Meister Lucius & Brüning, Frankfurt am Main, Germany, a corporation of Germany

No Drawing. Filed Mar. 8, 1961, Ser. No. 94,131
Claims priority, application Germany, Mar. 11, 1960,
F 30,735

5 Claims. (Cl. 260—579.8)

The present invention provides new phenyl-alkylamines of the formula

in which OR₁ represents the hydroxy group, the methoxy, ethoxy or benzyloxy group, R₂ represents an alkyl group containing 1 to 4 carbon atoms and R₃ and R₄ are alkyl groups containing 1 to 4 carbon atoms or together with the adjacent central carbon atom are members of a saturated alicyclic ring system containing 5 to 6 carbon atoms, physiologically compatible acid-addition salts of these compounds and pharmaceutical preparations containing those new phenyl-alkylamines or the salts thereof as active ingredients.

The present invention further provides the preparation of phenyl-alkylamines of the Formula I according to methods which may generally be applied for the preparation of such compounds.

The products obtained according to the invention are precious medicaments which while being well tolerated are distinguished especially by valuable analgesic properties.

The compounds may be obtained, for example, by (a) reducing primary amines of the Formula II

in which OR₁ and R₂ have the meanings given above, in the presence of ketones of the Formula III

in which R₃ has the meaning given above and R₅ represents an alkyl group containing 1 to 4 carbon atoms or an alkylene group containing 2 to 4 carbon atoms, or (b) reacting primary amines of the Formula II with esters of the Formula IV

in which R₃ and R₄ have the meanings given above and X represents an inorganic or organic acid radical, if desired in the presence of an acid-binding agent, or (c) heating primary amines of the Formula II in the presence of alcohols of the Formula V

in which R₃ and R₄ have the meanings given above, with

2

an excess amount of Raney nickel, or (d) reducing alcohols of the Formula VI

in which OR₁ and R₂ have the meanings given above, with primary amines of the Formula VII

in which R₃ and R₄ have the meanings given above, or (e) reacting compounds of the Formula VIII

in which OR₁ and R₂ have the meanings given above and "Hal" represents a chlorine, bromine or iodine atom, with amines of the Formula IX

in which R₃ and R₄ have the meanings given above and R₆ represents a hydrogen atom or the benzyl group, if desired in the presence of an acid-binding agent and, in case R₆ represents a benzyl group splitting off the latter hydrolytically, or (f) reducing aldehydes of the Formula X

in which OR₁ and R₂ have the meanings given above, in the presence of amines of the Formula VII, or (g) reducing carboxylic acid amides of the Formula XI

45 in which OR₁, R₂, R₃ and R₄ have the meanings given above, with lithium-aluminum-hydride in order to obtain the amines of Formula I, and if in the products obtained according to the invention OR₁ represents the methoxy- or ethoxy-group, converting these in usual manner into the hydroxy group, or if OR₁ represents the hydroxy group, converting the latter, if desired, into the methoxy or ethoxy group, or, if OR₁ represents the benzyloxy group, splitting off the benzyl radical, if desired, by catalytic hydrogenation.

50 55 The alkyl radicals R₂, R₃ and R₄ may be equal or different, straight chained or branched. There may be mentioned, for example: methyl, ethyl, n-propyl, isopropyl, n-butyl, isobutyl and sec.butyl radicals. The substituent OR₁ may be in any desired position of the phenyl nucleus.

60 It is most advantageous for the preparation of the products according to the invention to react amines of the Formula II with ketones of the Formula III. As amines may be used, for example:

65 2-(2', 3'- or 4'-hydroxy-phenyl)-2-ethyl-butylamine-(1),
2-(2', 3'- or 4'-hydroxy-phenyl)-2-n-propyl-butylamine-(1),
2-(2', 3', or 4'-hydroxyphenyl)2-isopropyl-butylamine-(1),
2-(2', 3'- or 4'-methoxy-phenyl)-2-ethyl-butylamine-(1),
2-(2', 3'- or 4'-methoxy-phenyl)-2-n-butyl-butylamine-(1),

- 2-(2', 3'- or 4'-methoxy-phenyl)-2-isobutyl-butylamine-(1),
 2-(2', 3'- or 4'-methoxy-phenyl)-2-n-propyl-butylamine-(1),
 2-(2', 3'- or 4'-methoxy-phenyl)-2-isopropyl-butylamine-(1),
 2-(2', 3'- or 4'-ethoxy-phenyl)-2-methyl-butylamine-(1),
 2-(2', 3'- or 4'-ethoxy-phenyl)-2-ethyl-butylamine-(1),
 2-(2', 3'- or 4'-ethoxy-phenyl)-2-ethyl-butylamine-(1),
 2-(2', 3'- or 4'-benzyloxy-phenyl)-2-n-butyl-butylamine-(1),
 2-(2', 3'- or 4'-benzyloxy-phenyl)-2-isobutyl-butylamine,
 2-(2', 3'- or 4'-benzyloxy-phenyl)-2-sec-butylamine-(1),
 2-(2', 3'- or 4'-benzyloxy-phenyl)-2-ethyl-butylamine-(1),
 2-(2', 3'- or 4'-benzyloxy-phenyl)-2-isopropyl-butylamine-(1) and
 2-(2', 3'- or 4'-benzyloxy-phenyl)-2-methyl-butylamine-(1).

As ketones of the Formula III there may be used, for example, the following compounds: acetone, methylethylketone, methyl-propyl-ketone, methylbutyl-ketone, methylisopropyl-ketone, methyl-isobutyl-ketone, diethyl-ketone, dipropyl-ketone, methyl-vinyl-ketone, isopropylidene-acetone (mesityloxide), cyclo-pantanone, cyclo-hexanone.

The amines to be used as starting substances may favorably be prepared by hydrogenation of the correspondingly substituted cyanides in the presence of catalysts of the 8th Group of the Periodic System. The cyanides may be prepared by reacting the correspondingly substituted benzyl-cyanides with sodium amide and alkyl halides in a solvent immiscible with water. If the radical R_2 represents an ethyl group, it is possible to introduce both radicals in a single operation stage into the substituted benzyl-cyanide, by reaction of 2 mols of sodium amide with two mols of ethyl-halide. If the radical R_2 differs from ethyl, the substituted benzyl-cyanides are obtained in two stages, by introducing, for example, into the corresponding benzyl cyanide with the aid of one mol of sodium amide and one mol of ethyl-bromide at first an ethyl group and subsequently, again with the aid of sodium amide, for example by means of isopropyl-bromide, the isopropyl group. If the hydroxy group in the phenyl nucleus is in para-position, the starting substances suitable for the process may likewise be obtained from the non-substituted benzyl-cyanide. For instance, there may be obtained phenyldiethyl-acetonitrile from benzyl-cyanide by means of two mols of sodium amide and two mols of ethyl-bromide. By nitration with nitric acid and sulfuric acid there is obtained from the last-mentioned compound the 4-nitrophenyl-diethyl-acetonitrile which may be reduced at 20-30° C. by means of nickel catalysts under a gauge pressure of 10-20 atmospheres of hydrogen in order to obtain 4-amino-phenyl-diethyl-acetonitrile. From the latter there is obtained after diazotization and boiling the 4-hydroxy-phenyl-diethyl-acetonitrile from which the 2-(4'-hydroxyphenyl)-2-ethyl-butylamine-(1) is formed by catalytic hydrogenation.

The reduction of the starting substances thus obtainable may be effected in the presence of ketones of the Formula III, for instance, catalytically with the aid of metals of the 8th Group of the Periodic System, preferably with palladium catalysts and an excessive amount of ketone as solvent, at a temperature of 50° C. and under a low or an elevated gauge pressure of hydrogen up to 50 atmospheres. When operating according to this method, the excessive ketone is not hydrogenated to yield the corresponding carbinol and may be recovered. Instead of palladium there can likewise be used nickel catalysts (Raney nickel). It is likewise possible to carry out the reduction by means of nascent hydrogen, for instance aluminum amalgam and alcohol, sodium amalgam, lithium-aluminum-hydride or sodium boron hydride. The reduction may, furthermore, be carried out by electrolysis.

According to another favorable method of carrying out

the process according to the invention amines of the Formula II may be reacted with esters of inorganic or organic acids of the Formula IV. There may be used for example: isopropyl-iodide, sec. butyl-bromide, 3-bromopentane, 2-bromo - 3 - methyl-butane, 2-bromo-4-methylpentane, cyclopentyl-bromide, cyclohexyl-bromide, p-tolene-sulfonic acid isopropyl-ester, diisopropyl-sulfate.

This reaction is suitably performed by heating the reactants in an appropriate solvent, for instance ethanol, propanol, benzene, toluene or xylene at temperatures between 80 and 130° C. The heating period depends on the temperature and the reactivity of the ester component and amounts, in general, to 2 to 20 hours. In order to bind the acids that have formed during the reaction the amine of the Formula II may be used in excess and a solvent immiscible with water may be used. The corresponding amine salt formed in the course of the reaction is generally obtained in a crystalline form and may be removed after cooling by filtering with suction or by shaking out the reaction solution by means of water, whereupon the desired reaction product may be isolated as a salt by distilling off the solvent or by shaking out the solvent with the aid of acids. Instead of a second mol of the amine there may be used in order to bind the acids formed, likewise other basic compounds, for instance sodium bicarbonate, anhydrous sodium carbonate or tertiary amines such as triethylamine or diethylaniline. The reaction may likewise be carried out without using solvents by heating both reaction components to temperatures between 80 and 130° C., it being favorable to use the amine in a bimolar excess.

Another method of carrying out the process according to the invention consists in heating amines of the formula II in the presence of alcohols of the Formula V with an excessive amount of Raney nickel for a prolonged period of time, e.g., 15 hours, at temperatures of 100-120° C.

According to a further method of operation alcohols of the Formula VI can be reacted with primary amines of the Formula VII, advantageously by heating them with an excessive amount of Raney nickel in order to obtain the desired products. It is suitable to add an excessive amount of the corresponding amine which then simultaneously serves as a solvent.

Furthermore, it is possible, to react halogen compounds of the Formula VIII with amines of the Formula IX. The reaction is performed, in principle, under the same reaction conditions as described above. When starting from amines containing a benzyloxy group, the benzyl-group may subsequently be split off by hydrogenation, favorably in an organic solvent, such as methanol, in the presence of noble metal catalysts.

The halogenated hydrocarbons of the Formula VIII may be prepared, for instance, by reducing the corresponding phenyl-dialkyl-acetic acids with lithium-aluminium-hydride in ethereal solution and treating the phenyl-dialkyl-ethanols thus obtained with concentrated hydrobromic acid at temperatures between 80 and 100° C.

A further possibility of preparing the products according to the invention consists in reducing aldehydes of the Formula X, for instance 3-methoxy-phenyl-diethyl-acetaldehyde, in the presence of amines of the Formula IX. It is recommendable to carry out the reduction catalytically while using catalysts of the 8th Group of the Periodic System and in the presence of a solvent, for instance, methanol. The aldehydes used as starting substances may be obtained, for example, from the corresponding carbinols by oxidation with selenedioxide.

Finally, amides of the Formula IX may be converted in the usual manner by reduction with lithium-aluminium-hydride into the desired products. As such amides there may be mentioned, for instance, 3-methoxy-phenyl-diethyl-acetic acid-isopropylamide, 3-methoxy-phenyl-diethyl-acetic acid-sec. butylamide, 4-methoxy-phenyl-diethyl-acetic acid-sec. butylamide.

For the preparation of products in the formula of which OR_1 represents the hydroxy group, it is of advantage first to prepare the corresponding methoxy-, ethoxy- or benzyl-

oxy-compound. The methoxy- and ethoxy-compounds may be dealkylated in the usual manner, for instance by heating with hydrogen chloride, hydrogen bromide, aluminium chloride or pyridin-hydrochloride in order to obtain the corresponding hydroxy compounds.

If, for preparing the products according to the invention, benzyloxy-compounds are used, for instance 2-(3'-benzyloxy-phenyl)-2-ethyl-butylamine-(1), the hydroxy-derivatives may be obtained according to the method applied in one or two stages of operation. When introducing, for instance, the radical

by catalytic hydrogenation with corresponding ketones and palladium as catalyst, the benzyl group is simultaneously split off. If the radical

is however, introduced according to another method, for instance by reaction with esters of the Formula IV, in the case of which the benzyloxy group does not react, the benzyl group is split off in a second stage by hydrogenation by means of noble metals as catalysts.

On the other hand, if according to one of the above-described methods of operation there are obtained products in the formula of which R_1 represents the hydroxy group, the latter can be converted into the methoxy- or ethoxy- group by methylation or ethylation in the usual manner, for instance with dimethyl-sulfate or diethyl-sulfate in an alkaline solution.

The products obtained according to the process of the present invention can be converted into the corresponding acid addition salts by treatment with inorganic or organic acids. For the salt formation may be used, for example, inorganic acids such as hydrohalic acid, particularly hydrochloric and hydrobromic acid, sulfuric acid, phosphoric acid, amido-sulfonic acid. As organic acids enter into consideration: acetic acid, propionic acid, oxalic acid, malic acid, succinic acid, lactic acid, maleic acid, fumaric acid, sorbic acid, citric acid, aceturic acid, aspartic acid, p-amino-benzoic acid, salicylic acid and ethylenediamine-tetracetic acid.

The products obtained according to the invention are precious medicaments which, while being well tolerated, are distinguished by valuable analgesic properties.

The analgesic activity was examined in Swiss albino mice according to a modification of the method of Wolff-Hardy-Goodell (J. Clin. Invest. 19 (1940) 659). When applying this method a number of albino mice were given the preparation subcutaneously or orally and the period of time in which the animals reacted on the thermal irritation was examined prior to and after the administration of the products. This method was modified in such a way that by a process of "all or nothing" certain criteria were found in order to ascertain the percentage of animals reacting on the test. Thus, relatively exact relations of dosis efficiencies could be found. Upon subcutaneous administration the N-sec. butyl-2-(3'-hydroxy-phenyl)-2-ethyl-butylamine-(1) proved to be 7 to 8 times stronger than the known 1-phenyl-2,3-dimethyl-4-dimethylamino-pyrazolone-(5) and upon oral application two times stronger than the known 1-methyl-4-phenyl-piperidino-4-carboxylic acid ethyl-ester as regards analgesic action. The above-mentioned compound when applied in mice excited by administration of 1-phenyl-2-methylamino-propane according to the method by Thei (Südd. Apoth. Zeitg. 1953, page 292) shows a distinctly sedative activity and an antipyretic effect in the case of artificially produced fever in rabbits.

The very excellent analgesic action of the new phenyl-alkylamines could also be corroborated by clinical tests.

The compounds are preferably administered in the form of dragees or tablets, each tablet containing from 5 to 100 milligrams thereof as active ingredients.

The following examples serve to illustrate the invention but they are not intended to limit it thereto:

Example 1

(a) N-isopropyl-2-(3'-methoxyphenyl)-2-ethyl-butylamine-(1): 20 grams of 2-(3'-methoxy-phenyl)-2-ethyl-butylamine-(1) are shaken in 100 grams of acetone with palladium as catalyst and hydrogen under a weak superatmospheric pressure at 50° C., until hydrogen is no more absorbed, or hydrogenated at 50° C. under a hydrogen pressure of 50 atmospheres gauge. After separation from the catalyst and elimination of the excessive acetone by distillation there is obtained the N-isopropyl-2-(3'-methoxy-phenyl)-2-ethyl-butylamine-(1) in quantitative yield. A hydrochloride is formed which melts at 129° C.

The same compound is obtained by heating 2-(3'-methoxy-phenyl)-2-ethyl-butylamine-(1) for 15 hours with excessive isopropanol and a great amount of Raney nickel, or by reacting 1-bromo-2-(3'-methoxy-phenyl)-2-ethyl-butane in boiling xylene with isopropylamine.

The 1-bromo-2-(3'-methoxy-phenyl)-2-ethyl-butane is obtained by treating m-methoxyphenyl-diethylacetic acid in ethereal solution with lithium-aluminum-hydride and reaction of the carbinol obtained with concentrated hydrobromic acid.

(b) N-sec. butyl-2-(3'-methoxy-phenyl)-2-ethyl-butylamine-(1): 300 grams of 2-(3'-methoxy-phenyl)-2-ethyl-butylamine-(1) are hydrogenated in 750 grams of methyl-ethyl-ketone and worked up according to the above-mentioned direction. The N-sec. butyl-2-(3'-methoxy-phenyl)-2-ethyl-butylamine-(1) is obtained in quantitative yield. Its hydrochloride melts at 139° C.

The same compound is obtained by hydrogenating at 50° C. 2-(3'-methoxy-phenyl)-2-ethyl-butylamine-(1) with methyl-vinyl-ketone and palladium as catalyst until no more hydrogen is absorbed, or by treating 3-methoxy-phenyl-diethyl-acetic acid-sec. butylamide with lithium-aluminum hydride, or by heating to boil for 15 hours 2-(3'-methoxy-phenyl)-2-ethyl-butanol-(1) with an excessive amount of sec. butylamine in the presence of large amounts of Raney-nickel. There were furthermore obtained from 2-(3'-methoxy-phenyl)-2-ethyl-butylamine-(1) by hydrogenation with the corresponding ketones:

(c) N-[3"-methyl-butyl-(2"')]-2-(3'-methoxy-phenyl)-2-ethyl-butylamine-(1); melting point of the hydrochloride: 132° C. (from methyl-isopropyl-ketone).

(d) N-[4"-methyl-pentyl-(2"')]-2-(3'-methoxy-phenyl)-2-ethyl-butylamine-(1); melting point of the hydrochloride: 86° C. (from methyl-isobutyl-ketone).

(e) N-pentyl-(3")-2-(3'-methoxy-phenyl)-2-ethyl-butylamine-(1); melting point of the hydrochloride: 118° C. (from diethyl-ketone).

(f) N-cyclopentyl-2-(3'-methoxy-phenyl)-2-ethyl-butylamine-(1); melting point of the maleinate: 128° C. (from cyclopantanone).

(g) N-cyclohexyl-2-(3'-methoxy-phenyl)-2-ethyl-butylamine-(1); melting point of the hydrochloride: 140° C. (from cyclohexanone).

(h) N-pentyl-(2")-2-(3'-methoxy-phenyl)-2-ethyl-butylamine-(1); melting point of the hydrochloride: 126° C. (from methyl-propyl-ketone).

By heating the 3-methoxy compounds described in Examples 1 (a) to (h) for 8 hours with hydrobromic acid of 48% strength with reflux, the methyl group is split off with formation of the corresponding hydroxy-phenyl derivatives. The following products were produced, for example:

N-isopropyl-2-(3'-hydroxy-phenyl)-2-ethyl-butylamine-(1); melting point of the hydrochloride: 154° C.;

N-sec. butyl-2-(3'-hydroxy-phenyl)-2-ethyl-butylamine-(1); melting point of the hydrochloride: 165° C.;

N-[3"-methyl-butyl-(2"')]-2-(3'-hydroxy-phenyl)-2-ethyl-

butyl-amine-(1); melting point of the hydrochloride: 185° C.;
 N-[4"-methyl-pentyl (2'')] - 2 - (3' - hydroxy-phenyl) - 2 - ethyl-butyl-amine-(1); melting point of the hydrochloride: 164° C.;
 N-pentyl-(3'') - 2 - (3' - hydroxy-phenyl) - 2 - ethyl-butylamine-(1); melting point of the hydrochloride: 180° C.;
 N-cyclopentyl-2 - (3' - hydroxy-phenyl) - 2 - ethyl-butylamine-(1); melting point of the hydrochloride: 179° C.;
 N-cyclohexyl-2 - (3' - hydroxy-phenyl) - 2 - ethyl-butylamine-(1); melting point of the hydrochloride: 198° C.;
 N-pentyl-(2'') - 2 - (3' - hydroxy-phenyl) - 2 - ethyl-butylamine-(1); melting point of the hydrochloride: 167° C.

The 2 - (3' - methoxy - phenyl) - 2 - ethyl - butylamine-(1) boiling at 145 - 152° C. under a pressure of 10 mm. of mercury used as starting substance is obtained by hydrogenation of (3' - methoxy-phenyl)-diethyl-acetonitrile (B.P. 128 - 130° C. under a pressure of 4 mm. of mercury) which is formed from 3-methoxy-benzylcyanide by reaction with 2 mols of sodium amide and 2 mols of ethyl-bromide.

Example 2

N - isopropyl - 2 - (3' - methoxy - phenyl) - 2 - ethyl-butylamine-(1): 20 grams of 2-(3' - methoxy-phenyl) - 2 - ethyl-butylamine-(1) are heated with 1 mol of diisopropyl-sulfate for 3 hours to 100° C. There is obtained in good yield the N-isopropyl-2-(3'-methoxy-phenyl)-2-ethyl-butylamine-(1) whose hydrochloride melts at 129° C.

Example 3

(a) N - sec. butyl - 2 - (3' - methoxy - phenyl) - 2 - ethyl-3-methyl-butyl-amine (1): 20 grams of 2-(3' - methoxy-phenyl) - 2 - ethyl-3-methyl-butylamine-(1) are hydrogenated with 100 grams of methyl-ethyl-ketone as described in Example 1 (b). There is obtained in quantitative yield the N-sec. butyl-2-(3'-methoxy-phenyl)-2-ethyl-3-methyl-butylamine-(1) whose maleinate melts at 88° C.

There were likewise obtained from 2-(3' - methoxy-phenyl) - 2 - ethyl-3-methyl-butylamine-(1) by hydrogenation with the corresponding ketones the following compounds:

(b) N - isopropyl - 2 - (3' - methoxy - phenyl) - 2 - ethyl-3-methyl-butylamine-(1); melting point of the hydrochloride: 131° C. (from acetone).

(c) N - pentyl - (2'') - 2 - (3' - methoxy - phenyl) - 2 - ethyl-3-methyl-butylamine-(1); melting point of the maleinate: 90° C. (from methyl-propyl-ketone).

(d) N - pentyl - (3'') - 2 - (3' - methoxy - phenyl) - 2 - ethyl-3-methyl-butylamine-(1); melting point of the fumarate: 138° C. (from diethylketone).

(e) N - [3' - methyl - butyl - (2'')] - 2 - (3' - methoxy-phenyl) - 2 - ethyl-3-methyl-butylamine-(1); melting point of the fumarate: 142° C. (from methyl-isopropyl-ketone).

By boiling the solution with hydrobromic acid of 48% strength under reflux the methyl group is split off the 3-methoxy compounds described in Examples 3 (a) to (e) with formation of the corresponding hydroxy-phenyl derivatives. The following products were prepared, for example:

N - isopropyl - 2 - (3' - hydroxy - phenyl) - 2 - ethyl - 3 - methyl-butylamine-(1); melting point of the hydrochloride: 177° C.;

N-sec. butyl - 2 - (3' - hydroxy - phenyl) - 2 - ethyl - 3 - methyl-butylamine-(1); melting point of the hydrochloride: 158° C.;

N - pentyl - (2'') - 2 - (3' - hydroxy - phenyl) - 2 - ethyl - 3 - methyl-butylamine-(1); melting point of the hydrochloride: 193° C.;

N - pentyl - (3'') - 2 - (3' - hydroxy - phenyl) - 2 - ethyl - 3 - methyl-butylamine-(1); melting point of the hydrochloride: 164° C.;

N - [3' - methyl - butyl - (2'')] - 2 - (3' - hydroxy - phenyl) - 2 - ethyl - 3 - methyl-butylamine-(1); melting point of the hydrochloride: 177° C.;

nyl) - 2 - ethyl - 3 - methyl-butylamine-(1); melting point of the hydrochloride: 174° C.

The 2 - (3' - methoxy - phenyl) - 2 - ethyl - 3 - methyl-butylamine-(1) boiling at 148 - 153° C. under a pressure of 12 mm. of mercury and serving as starting material is obtained in the following manner: 3-methoxy-benzyl-cyanide is reacted with 1 mol of sodium amide and 1 mol of ethyl-bromide whereby (3-methoxy-phenyl)-ethyl-acetonitrile boiling at 151 - 152° C. under a pressure of 10 mm. of mercury is obtained. Starting from this substance there is obtained with 1 mol of sodium amide and 1 mol of isopropyl-bromide the (3-methoxy-phenyl)-ethyl-isopropyl-acetonitrile boiling at 127 - 128° C. under a pressure of 1.5 mm. of mercury which upon hydrogenation yields the 2-(3'-methoxy-phenyl)-2-ethyl-3-methyl-butylamine-(1).

Example 4

(a) N - sec. butyl - 2 - (3' - methoxy - phenyl) - 2 - ethyl-3-methyl-pentylamine-(1): 20 grams of 2-(3' - methoxy-phenyl) - 2 - ethyl-3 - methyl-pentylamine-(1) are hydrogenated with methyl-ethyl-ketone as described in Example 1 (b). There is obtained in quantitative yield the N - sec. butyl - 2 - (3' - methoxy - phenyl) - 2 - ethyl - 3 - methyl-pentylamine-(1) whose maleinate melts at 108° C.

The following compounds were likewise obtained from 2 - (3' - methoxy - phenyl) - 2 - ethyl - 3 - methyl - pentylamine-(1) by hydrogenation with the corresponding ketones:

(b) N - isopropyl - 2 - (3' - methoxy - phenyl) - 2 - ethyl - 3 - methyl - pentylamine - (1); melting point of the maleinate: 93° C.;

(c) N - pentyl - (2'') - 2 - (3' - methoxy - phenyl) - 2 - ethyl-3-methyl-pentylamine-(1); melting point of the hydrochloride: 187° C.;

(d) N - [3' - methyl - butyl - (2'')] - 2 - (3' - methoxy-phenyl) - 2 - ethyl-3-methyl-pentylamine-(1); melting point of the fumarate: 145° C.

The methyl group is separated from the 3-methoxy compounds described in Examples 4 (a) to (d) by boiling with hydrobromic acid of 48% strength with reflux and formation of the corresponding hydroxyphenyl derivatives. For example, the following products were obtained:

N - isopropyl - 2 - (3' - hydroxy - phenyl) - 2 - ethyl - 3 - methyl-pentylamine-(1); melting point of the maleinate: 155° C.;

N - sec. butyl - 2 - (3' - hydroxy - phenyl) - 2 - ethyl - 3 - the hydrochloride: 176° C.;

N - pentyl - (2'') - 2 - (3' - hydroxy - phenyl) - 2 - ethyl - 3 - methyl-pentylamine-(1); melting point of the hydrochloride: 197° C.;

N - [3' - methyl - butyl - (2'')] - 2 - (3' - hydroxy - phenyl) - 2 - ethyl-3-methyl-pentylamine-(1); melting point of methyl-pentylamine-(1); melting point of the hydrochloride: 175° C.;

The 2 - (3' - methoxy - phenyl) - 2 - ethyl - 3 - methyl-pentylamine-(1) boiling at 173 - 177° C. under a pressure of 11 mm. of mercury and serving as starting substance is obtained by hydrogenation of (3-methoxy-phenyl)-ethyl-sec. butyl-acetonitrile boiling at 143 - 145 C. under a pressure of 2.5 mm. of mercury which is obtained from (3-methoxy-phenyl)-ethyl-acetonitrile by reaction with sodium amide and sec. butyl-bromide.

Example 5

N - sec. butyl - 2 - (4' - methoxy - phenyl) - 2 - ethyl-butylamine-(1): 20 grams of 2-(4'-methoxy-phenyl)-2-ethyl-butylamine-(1) are hydrogenated with methyl-ethyl ketone as described in Example 1 (b). There is obtained in quantitative yield the N-sec. butyl-2-(4'-methoxy-phenyl)-2-ethyl-butylamine-(1) whose maleinate melts at 132° C.

The same compound is obtained by catalytic hydrogena-

tion of anisyl-diethyl-acetaldehyde in the presence of sec. butylamine.

From N - sec. butyl - 2 - (4' - methoxy-phenyl) - 2 - ethyl-butylamine-(1) there is obtained, by boiling with hydrobromic acid of 48% strength, the N-sec. butyl-2-(4'-hydroxy-phenyl)-2-ethyl-butylamine-(1) whose hydrochloride melts at 158° C.

The 2 - (4' - methoxy-phenyl)-2-ethyl-butylamine-(1) serving as starting substance and showing a boiling point of 118-120° C. under a pressure of 4 mm. of mercury is obtained by catalytic hydrogenation of (4-methoxy-phenyl)-diethyl-acetonitrile showing a boiling point of 127-129° C. under a pressure of 3 mm. of mercury, which is obtained by reaction of 4-methoxy-benzyl-cyanide with 2 mols of sodium amide and two mols of ethyl-bromide.

Example 6

N-sec. butyl-2-(4'-hydroxy-phenyl)-2-ethyl-butylamine-(1): 2-(4'-hydroxy-phenyl)-2-ethyl-butylamine-(1) melting at 122° C. is hydrogenated in the presence of methyl-ethyl-ketone and palladium as catalyst, whereby N-sec. butyl-2-(4'-hydroxy-phenyl)-2-ethyl-butylamine-(1) is obtained whose hydrochloride melts at 158° C.

The 2 - (4' - hydroxy-phenyl)-2-ethyl-butylamine-(1) used as starting substance is obtained by catalytic hydrogenation of (4-hydroxy-phenyl)-diethyl-acetonitrile showing a melting point of 71° C. The latter may be prepared from (4-amino-phenyl)-diethyl-acetonitrile of a melting point of 113° C. by diazotization and boiling down.

Example 7

N-sec. butyl 2-(3'-ethoxy-phenyl)-2-ethyl-butylamine-(1): 20 grams of 2-(3'-ethoxy-phenyl)-2-ethylbutylamine-(1) are hydrogenated in 100 grams of methyl-ethyl-ketone with palladium as catalyst as described in example 1 (a). The mixture is then treated up. There is obtained in quantitative yield the N-sec. butyl-2-(3'-ethoxy-phenyl)-2-ethyl-butylamine-(1) whose hydrochloride melts at 81° C.

The 2-(3'-ethoxy-phenyl)-2-ethyl-butylamine-(1) serving as starting substance is obtained in the following manner: 3-hydroxy-benzyl-alcohol in alkaline solution with diethylsulfate gives the 3-ethoxy-benzyl-alcohol which in benzenic solution by treatment with concentrated hydrobromic acid at 50° C. forms 3-ethoxy-benzyl bromide. From this compound there is obtained by reaction with potassium cyanide the 3-ethoxy-benzyl-cyanide. By reaction with the bimolar amount of ethyl-bromide with 2 mols of sodium amide in benzenic solution it furnishes the 3-ethoxy-phenyl diethyl-acetonitrile from which there is obtained by catalytic hydrogenation with Raney nickel and a solution of methanol and ammonia the 2-(3'-ethoxy-phenyl)-2-ethyl-butylamine-(1).

Example 8

N-sec. butyl-2-(3'-hydroxy-phenyl)-2-ethyl-butylamine-(1): 20 grams of 2-(3'-benzyloxy-phenyl)-2-ethyl-butylamine-(1) are hydrogenated in 100 grams of methyl-ethyl-ketone with palladium as catalyst as described in Example 1 (a) and worked up. There is obtained in

quantitative yield N-sec. butyl-2-(3'-hydroxy-phenyl)-2-ethyl-butylamine-(1) whose hydrochloride melts at 165° C.

The 2 - (3'-benzyloxy-phenyl)-2-ethyl-butylamine-(1) serving as starting substance is obtained in the following manner: 3-hydroxy-benzyl alcohol is reacted with benzyl-bromide in order to obtain 3-benzyloxy-benzyl-alcohol which at 50° C. in benzenic solution and when treated with concentrated hydrobromic acid is converted into the 3-benzyloxy-benzyl-bromide. The latter compound is converted by means of potassium cyanide into the 3-benzyloxy-benzyl-cyanide. The bimolar quantity of ethyl-bromide in benzenic solution and 2 mols of sodium amide are caused to act on this compound, whereby the 3-benzyloxy-phenyl-diethyl-acetonitrile is formed from which the 2-(3'-benzyloxy-phenyl)-2-ethyl-butylamine-(1) is formed by catalytic hydrogenation with Raney nickel as catalyst and a solution of methanol and ammonia.

We claim:

20. 1. A member selected from the group consisting of phenylalkylamines of the formula

25 in which R_2 is an alkyl group containing 1-4 carbon atoms, and R_3 and R_4 are members selected from the group consisting of alkyl groups containing 1-4 carbon atoms and together with the adjacent carbon atom form an alicyclic saturated ring system containing 5-6 carbon atoms, and the salts of these compounds with physiologically compatible acids.

2. N-sec. butyl - 2-(3'-hydroxy-phenyl)-2-ethyl-butylamine-(1).

3. N - isopropyl-2-(3'-hydroxy-phenyl)-2-ethyl-3-methyl-butylamine-(1).

4. N - isopropyl-2-(3'-hydroxy-phenyl)-2-ethyl-3-methyl-pentylamine-(1).

5. N-sec. butyl-2-(3'-hydroxy-phenyl)-2-ethyl-3-methyl-pentylamine-(1).
